BELT

James L. McNickle, Denver, Colo.

Application March 25, 1955, Serial No. 35,202

Term of patent 7 years

(Cl. D3—10)

FIG. 1

FIG. 2

Figure 1 is a front perspective view of a belt showing my new design; and

Figure 2 is a fragmentary top plan view thereof.

I claim:

The ornamental design for a belt, as shown.
